UNITED STATES PATENT OFFICE.

GEORGE IRVING THOMSON, OF CHICAGO, ILLINOIS.

GOLF-STROKE-REGISTERING DEVICE.

Application filed May 15, 1925. Serial No. 30,593.

My invention relates to improvements in golf stroke registering devices, and it consists in the combinations, constructions, and arrangements herein described and claimed.

5 An object of my invention is to provide an improvement over that form of the device shown in my co-pending application, Serial No. 705,291, filed April 9, 1894. In my co-pending application I show a device that is 10 adapted to register the force at which the golf ball strikes the striker plate, this registering means consisting of a series of lights, each light indicating the number of yards the ball would travel if struck out on 15 the open fairway. For example, if the player struck the ball hard enough to normally send the ball 125 yards, the light indicating 125 yards would be energized. If the drive was for 150 yards, etc., the light 20 corresponding to this yardage would be illuminated.

In the present form of the device I provide a device in which the lights showing the greatest number of yardage are energized only when an exceptionally strong 25 drive is made.

A further object of my invention is to provide a device of the type described in which the lights may be disposed upon a green 30 background that resembles the golf course, the background being provided with a picture of a clubhouse thereon, bunkers, sand traps, etc., thus resembling the golf course.

A further object of my invention is to provide 35 a deadening device for stopping the rebound of the golf ball when it hits the striker plate.

A further object of my invention is to provide 40 a device of the type described in which the golf ball is kept away from striking hard surfaces, such as metal or wooden parts of the machine.

A further object of my invention is to provide 45 a device of the type described which has a novel return mechanism for conveying the golf balls back to the driver.

Other objects and advantages will appear 50 in the following specification, and the novel features of the invention will be particularly pointed out in the appended claims.

My invention is illustrated in the accompanying drawings forming part of this application, in which

Figure 1 is a side elevation of the device,

Figure 2 is an enlarged detail view of a portion of the device,

Figure 3 is a section along the line 3—3 of Figure 1,

Figure 4 is a section along the line 4—4 of Figure 1,

Figure 5 is a section along the line 5—5 of Figure 4.

Figure 6 is a section along the line 6—6 of Figure 2,

Figure 7 is a plan view of the scoreboard, and

Figure 8 is a section along the line 8—8 of Figure 2.

In carrying out my invention I provide a funnel-shaped canvas guide 1, substantially quadrangular in cross section, the larger end 2 of this canvas guide being provided with a pair of flaps 3 that are secured to a pair of columns 4. In the present form of the device I show these columns as extending from the floor to the ceiling of the room, but it is obvious that the columns may be carried by a self-supporting frame if desired.

The object of the game is to permit the player to practice during the winter season, or to use the device any time that he does not care to go out upon the fairway or cannot go out upon the fairway. The player stands approximately 30 or more yards away from the post 4 and drives the golf ball toward the funnel-shaped member 1. If the golf ball enters the member 1 it is directed toward a back stop 5 that is preferably made out of heavy canvas.

I have found that when a plate made of metal or wood is used as a back stop, the ball will careen off from this back stop and will endanger the driver. A canvas back stop will operate just as efficiently as a back stop made of wood or metal and will at the same time stop the rebound of the ball. As stated heretofore, the canvas is very heavy so as to remain stiff and provide a smooth surface against which the golf ball strikes. This canvas is adapted to move away from a frame 6 that, in the present form of the device, is made of wood and is supported in an upright 7. The upright extends from the floor, and is of sufficient height to position the opening 8 within the frame at the desired height above the floor. In the present form of the device I show the upright 7

as being constructed of angle irons, two of these angle irons 9 carrying the frame 6. Screws or other like fastening means 10 secure the frame 6 to the upright 7.

5 The back stop 5 is yieldingly carried by the frame 6 by means of springs 11. These springs are secured to three sides of the back stop, as clearly shown in Figure 4. The springs 11 permit the back stop 5 to move 10 away from the frame 6 when the golf ball strikes the back stop. The springs are strong enough to cause the back stop to return to normal position after it has been moved by the impact of the ball, whereby the device is 15 ready for the next play. In order to prevent the golf balls from flying in any direction when they strike the back stop I provide extensible sides 12 that are positioned on three sides of the back stop 5 and are secured to the frame 6. Figure 5 clearly shows how the sides 12 are corrugated so as to permit the back stop to move away from the frame 6. The sides 12 and the back stop 5 form a compartment in which the golf ball 20 25 30 35 40 45 50 55 60 65 70 75 80 85 90 95 100 105 110 115 120 125 130

is temporarily received. This compartment has an open lower end through which the ball falls, whereupon it is conveyed back to the driver. Means for conveying the ball back to the driver is shown in Figure 1 and consists of a gravity trough 13 and a hopper 14 that is positioned directly beneath the back stop 5. The golf ball upon striking the back stop 5 will be conducted to the hopper 14 and from thence will roll by gravity along the trough 13 and back to the driver.

At this point it is well to mention the means by which the member 1 is spaced away from the wall of the opening 8. This means is clearly shown in Figure 5. It will be noted that the small opening 15 of the funnel-shaped member 1 is of less diameter than the diameter of the opening 8. Adjacent to the small opening 15 the sides of the canvas are flared outwardly as at 16, and these flared-out sides are secured to the frame 6 by means of screws 17 or other like fastening means. This construction spaces the canvas 1 away from the wall of the opening 8, and if, therefore, the golf ball strikes the canvas adjacent to the opening 15, it will be prevented from striking the frame 6. In this way the rebound of the ball is entirely done away with, since at no time can the ball strike a metal or wooden surface.

55 I also provide means for securing the small end of the funnel-shaped member 1 to the upright 7, this means relieving the strain upon the neck of the funnel-shaped member 1. To this end I provide a canvas collar 18 that is sewed or otherwise secured to the funnel-shaped member 1 at 19 and has its free end provided with a number of eyelets 20. Hooks 21 are carried by the frame 6 and are received in the eyelets 20 so as to secure the collar 18 to the frame 6. The

posts 4 and the collar 18, together with the hooks 21, support the funnel-shaped member 1 at both ends thereof, and thus relieve the strain which would normally be brought to bear upon the screws 17.

The stroke registering apparatus of the device is substantially the same as disclosed in my co-pending application, Serial No. 705,291. However, the wheel 22 is supported by the framework 23 of the upright 7, instead of being supported by the bicycle fork as shown in my co-pending application. The wheel carries a disc 24 on its periphery, this disc carrying two laterally projecting pins 25 and 26. When the disc is in the full line position shown in Figure 8 the pin 25 is adapted to contact with the switch members 27. The means for causing the wheel to rotate differs slightly from the means shown in my co-pending application, and in the present form of the device is composed of two semicircular hoop-shaped members 28 that are disposed at right angles to each other and have their free ends secured to a third hoop-shaped member 29. The hoop 29 in turn is secured to the back stop 5 by means of angle irons 30 and flexible strips, such as canvas 31. I have found that the strain upon the hoop 29 is greatly relieved when the hoop is secured to the back stop 5 by the means just described. The hoops may differ in size for a purpose hereinafter described. The strips 31 have a number of openings 32 therein so as to permit the hoop to be readily secured to the back stop. If the hoop is a little large, the outer circle of openings is used. The strips 31 are secured to the back stop 5 by stitching 33, and have their free ends secured to the angle irons 30 by means of rivets 34, bolts, or the like. One of the hoops 28 is adapted to act as a cam member for actuating the striker lever. The striker lever is of the same construction as shown in my copending application, except that it is provided with a roller 36'. In the present form of the device this roller contacts with the hoop 28 so as to actuate the striker lever when the back stop is moved.

From the foregoing description of the various parts of the device the operation thereof may be readily understood. Assume that the player has driven the golf ball against the back stop 5 hard enough to move the back stop into the full line position shown in Figure 5. It should be noted at this point that the back stop normally is disposed adjacent to the rear wall of the frame 6 and is only moved into the full line position shown in Figure 5 when it is struck by a golf ball. The movement of the back stop 5 swings the lever 35, which in turn imparts movement to the wheel 22, due to the fact that the swinging of the lever 35 moves the striker member 36. As the striker member 36 is secured to the wheel, the wheel

is rotated in the direction of the arrow shown in Figure 2 the pin 25 will contact with the switch members 27 as the pin is carried past the switch members. Of course the momentum of the wheel 22 will be in direct ratio to the force at which the golf ball strikes the back stop 5. If the force is great the wheel will be turned through a relatively great arc, if small, the wheel will only be swung through a small arc. The switch members 27 will not be moved when the wheel rotates in the direction of the arrow, but as soon as the wheel starts to return to its normal position, the pin 25 will swing the first switch arm 27 that it strikes, thus closing the circuit (not shown) and energizing the light 37 on the score board 7 that corresponds with the number of yards through which the golf ball would have traveled under normal conditions. This part of the device has been clearly set forth in my co-pending application, and therefore a minute description is not necessary at this time. The wheel 22 carries weights 38 that are used for returning the wheel back to normal position after the wheel has been rotated.

In addition to the weights 38, I provide an auxiliary weight 39 that is carried by a platform 40. A cord 41 passes from the weight 39 over a pulley 42 and has its free end secured to the rim of the wheel 22 at 43. It will be noted from Figure 2 that this cord is slack and therefore the weight 39 will be lifted when the wheel nears the end of its movement. I prefer to have this weight applied to the wheel when the pin 25 is positioned beneath the last three switch members 27. This additional weight will cause the wheel to quickly slow up and will therefore make the last three points on the device hard to secure. If desired, these last three points may be indicated by the three uppermost lights on the scoreboard 7.

As heretofore stated, the wheel on its return movement will carry the pin 25 into contact with the switch member 27 disposed nearest thereto, and further movement of the wheel is prevented until the wheel is released by a mechanism shown in Figs. 2 and 6. This mechanism is similar to that shown in my co-pending application, except that in addition a coil spring 44 is used for swinging the bell crank lever 45 back into the full line position shown in Figure 6. The bell crank lever 45 is connected to a trigger 46 by means of a link 47, whereupon movement of the bell crank lever in the direction of the arrow shown in Figure 6 will release the trigger 46 from the notch 47 in the disc 24. The disc 24 is now free to swing and the weights 38 in returning the wheel back to normal position will cause the disc 24 to swing so as to release the pin 25 from the switch member 27.

In order to restore the wheel 22 to its initial position the cord 48 is pulled by the player so as to release the trigger 46 from the disc 24. The disc 24 will remain in the dotted line position until the pin 26 strikes a cam member 49. At the time the pin 26 strikes the cam member 49 the disc and the pin 25 will be free of the last switch member 27. The wheel will continue to rotate until the striker member 36 again contacts with the striker lever 35. In doing so the pin 26 will be swung by the cam 49 so as to return the disc 24 to the full line position. The trigger 46 will now reenter the notch 47 and will lock the disc 24 against further movement. The disc is now ready for another play. The trigger 46 is preferably made from a leaf spring, and in order to release the leaf spring 46 from all unnecessary weight I provide the coil spring 44 for returning the bell crank lever 45 to normal position. In this way the trigger 46 is free to swing back into normal position as soon as the disc 24 is swung so as to align the notch 47 with the trigger.

It will be observed by viewing Figures 2 and 5 that if hoops of substantially small diameters are employed, the striker lever will move a shorter distance than if hoops of substantially large diameters are employed. With smaller hoops, the roller 36 tends to move along the outer surface of one of the hoops, and will not be forced outwardly as far as it will with larger hoops.

I claim:

1. In a device of the type described a supporting frame, a funnel-shaped member secured to said supporting frame and being spaced therefrom so as to prevent a golf ball from striking the supporting frame, an impact member, means for movably securing said impact member to said support, said impact member being adapted to be moved by the impact of the golf ball, means for returning the member to initial position after it has been struck by the golf ball, means for conveying the golf ball back to the player, and means associated with said member for preventing the rebounding of the golf ball and for delivering the golf ball to said means.

2. In a device of the type described, an indicating device, an impact member, yielding means for holding said impact member, a movable member operatively connected to said impact member and being adapted to be moved by the impact of a golf ball, and means for retarding the movement of said movable member after said indicating device is moved through a predetermined distance.

3. In a device of the type described, a supporting frame, a funnel-shaped member passing through and secured to said supporting frame, said funnel-shaped member being spaced away from said supporting frame

so as to prevent a golf ball from striking the supporting frame, an impact member, flexible means for movably securing said impact member to said support, said impact member being adapted to be moved by the impact of said golf ball, spring means for returning the member to initial position after it has been struck by the golf ball, a hopper for conveying the golf ball back to the player, and means associated with said member for preventing the rebounding of the golf ball and for delivering the golf ball to said hopper.

4. In a device of the type described, an indicating device, an impact member, yielding means for holding said impact member, a movable member operatively connected to said impact member and being adapted to be moved by the impact of a golf ball, and a weight operatively secured to said movable member for retarding the movement of said movable member after said indicating device is moved through a predetermined distance.

5. In a golf stroke registering device, a frame having an opening therein, a bellows secured to the frame and surrounding the opening, a back stop at one end of said bellows and adapted to receive the impact of a golf ball on the front face thereof, and means actuated by the movement of said back stop for indicating the force of impact of the golf ball with said back stop.

6. In a golf stroke registering device, a frame having an opening therein, a bellows

secured to the frame and surrounding the opening, a back stop at one end of said bellows and adapted to receive the impact of a golf ball on the front face thereof, means actuated by the movement of said back stop for indicating the force of impact of the golf ball with said back stop, said means including a frame, a lever pivotally mounted on said frame, a wheel rotatably mounted upon said frame, and means secured to said back stop for pivoting said lever and rotating said wheel when said back stop is moved.

7. In a golf stroke registering device, a frame having an opening therein, a bellows secured to the frame and surrounding the opening, a back stop at one end of said bellows and adapted to receive the impact of a golf ball on the front face thereof, means actuated by the movement of said back stop for indicating the force of impact of the golf ball with said back stop, said means comprising a semi-circular hoop-shaped member carried by said back stop, a frame, a lever pivotally mounted upon said frame and having an outwardly extending integral projection, a roller rotatably mounted upon said projection and disposed in engagement with said hoop-shaped member, a wheel rotatably mounted upon said frame, and a striker member secured to said wheel and disposed in engagement with said lever whereby the movement of said back stop pivots said lever and rotates said wheel.

GEORGE IRVING THOMSON.
